FLAT HOSIERY FRAME

Willy Rottloff, Auerbach in Erzg, Germany, assignee to Karl Lieberknecht G. m. b. H., Obergungwitz, Germany, a corporation of Germany

Application August 14, 1933, Serial No. 685,027
In Germany August 19, 1932

6 Claims. (Cl. 66—96)

This invention relates to a flat hosiery frame provided with a narrowing mechanism which serves as auxiliary presser mechanism, and has for its object to bring about a variation in the structure of the goods by the temporary stopping of frame needles.

It has been proposed already to employ the usual narrowing mechanism with its covering needles as auxiliary presser mechanism for working in additional courses which do not extend over the entire width of the goods. This requires, however, that the covering needles, after the normal presser mechanism has been disengaged, pierce the old loops on the frame needles during the formation of the loops and pass them over the hooks of the frame needles. It has further been proposed to proceed in a similar manner when frame needles with inelastic hooks are used and to pass the old loops over the open hook by means of special presser points resembling working needles. But this process also involves piercing of the old loops by the presser points.

According to the invention, this detrimental piercing of the old loops on the frame needles by the covering needles or presser points is eliminated by providing the narrowing mechanism with special presser surfaces disposed above the grooves of the covering needles. The special presser surfaces may be of different kinds. For example, the usual covering needles may possess a corresponding deflection, or special presser points, presser plates, combs or the like may be disposed in front of the coverers and used as presser mechanisms. An important feature is that piercing of the old loops by the covering needles or presser points is no longer required, as the old loops are landed simply by closing the elastic frame needle hooks on the special presser surfaces arranged above the grooves of the covering needles.

By way of example, the invention is illustrated in the accompanying drawing, in which Figure 1 shows a covering needle having a presser surface for closing the hook of a frame needle above the knocking over bits; Fig. 2, a covering needle having a presser surface for closing the hook of a frame needle above the sinker throats; Figs. 3, 4 and 5 show different types of covering needles or presser points; Fig. 6 shows a plain covering needle with a special presser part rigidly disposed on the narrowing mechanism; Fig. 7 shows the same needle with a presser part movably disposed on the narrowing mechanism; and Fig. 8

shows a cross section of a full fashioned hosiery machine of Cotton's system.

With reference to the drawing, the known pressing process will first be briefly described: After the frame needles 2 have been provided with threads, the needle bar 1 will move down and, simultaneously, towards the sinker head 3 to such an extent that the elastic hooks of the frame needles 2 are closed on the presser edge 4 of the sinker head 3. Thus the loops 5 on the frame needles 2 will slide onto the hooks thereof and be thrown off during further descent of the needles 2. The newly formed loop handles 6 positioned under the hooks of the frame needles 2 are then drawn through the old loops 5 and made into new loops.

Figs. 1 and 2 show how the presser process is carried out by means of the narrowing and presser mechanism according to the invention. As indicated in Fig. 1, the frame needle 2 moves down in the usual way, with the difference, however, as compared with the previously described process that in order not to engage the normal presser mechanism it does not descend to the presser edge 4 of the sinker head 5 but remains at a certain distance from the edge. Simultaneously with the frame needle 2, the covering needle 7 moves down until its deflection 8 serving as a presser surface is on a level with the presser edge 4 of the sinker head 3 and in front of the hook of the frame needle 2 which places itself against this deflection 8 of the needle 7 in such a way that the hook is closed. Only the frame needle hook is closed, however, opposite to which a covering needle 7 with a deflection 8 is positioned while all other frame needles remain open and the loops located on these open needles are therefore not thrown off.

The presser process according to Fig. 2 differs from the process just described only in so far as the closing of the hook of the frame needle takes place already above the sinker throat, so that during the descent of the frame needle the newly formed loop handle is landed on the closed hook of the frame needle and, during further descent of the latter, thrown off.

The covering needles and presser points shown in Figs. 3 to 7 convey an idea of the many uses of the device according to the invention. Fig. 3 shows a covering needle 7 possessing a presser surface 8 disposed immediately above the groove 7". Fig. 4 shows a covering needle 7 having its presser surface 8 arranged somewhat higher than in Fig. 3. Both kinds of needles can be simultaneously used in such a way that, as described

already with respect to Figs. 1 and 2, within one downward motion of the frame needle 2 the covering needle 7 having a higher presser surface 8 will close the corresponding needle hook above the sinker throat while the covering needle with lower presser surface will close the corresponding hook above the knocking over bits and therefore at normal pressing height.

Furthermore, according to Figs. 5, 6 and 7, needles 1' may be used which are constructed solely as presser point and not as covering needles. The various kinds of needles may be disposed in any grouping in one and the same bar or in a plurality thereof which act jointly or independently of one another. Moreover, in addition to covering needles having a presser surface, covering needles without presser surfaces may be employed to provide a great variety of combinations to take care of many different purposes.

As indicated by the description of Figs. 6 and 7, the presser surface formed by the deflection 8 of the covering needles may be replaced by special parts. In the construction shown in Fig. 6 the narrower 19 carrying the covering needle 7 supports a screwed-on comblike plate 27 whose prongs 28 extend into the elevations 9' serving as presser surfaces. In Fig. 7, the comblike presser plate or the like is secured by a special holder 30 to the rotatable rod 31 which can be laterally displaced independently of the narrower, so that it is possible to render the presser bar operative or inoperative, according to requirements.

The invention may further be applied to 35 jacquard lace full-fashioned flat hosiery machines by causing the covering needles provided with presser surfaces, during the presser as well as narrowing steps, to be brought by the jacquard attachment within or out of range of the frame 40 needle hooks, so that these attachments can be used also for working jacquard tuck patterns and the like besides serving their main purpose of producing jacquard lace patterns.

For carrying out the process described above 45 the narrowing mechanism found in every flat hosiery frame is used after being suitably changed or supplemented, as shown in Fig. 8.

In the hosiery frame according to Fig. 8, 9 is the machine frame in which the shaft 13 is rotatably disposed and carries the arms 14 supporting on their front end the shaft 15. The shaft 15 is provided with the holders 16 in the guide of which the bars 17 and 18 are displaceably disposed with the narrowers 19. The frame 9 further carries 50 the bolts 20 to which the levers 21 are secured and provided with rotatable rolls 22 which rest on the cam 24 disposed on the main shaft 23 and which, by means of the connecting rods 25, carry the narrowing machine or determine the height of the 55 narrowers 19. Below the rear ends of the levers 21 the supports 26 oscillatorily secured to the

frame 9 are provided on which the levers 21 may rest as long as the supports 26 are within their range, i. e., as long as the narrowing machine is not moving up and down but inoperative. However, if the narrowing machine is to be lowered 5 for patterning, narrowing, widening or, according to the invention, for carrying out the presser process described, the supports 26 will be moved out of range of the levers 21 into the position indicated by dots and the narrowing machine can 10 then move according to the form and rotation of the cams 24. For the presser process, the cams 24 are fitted with an inward bulge 32 to insure lowering of the narrowing machine after the motion of the supports 26 at the time when the frame 15 needles 2 are lowered also. For narrowing, however, the standard narrowing cams, not shown, are provided which act in known manner by the lateral displacement of the main shaft 23.

As soon as the supports 26 are moved out of 20 range of the levers 21, the rolls 12 will be laterally displaced so as to engage the cams 11 having a low presser point and to bring about the descent of the frame needles 2 at the requisite distance from the presser edge 4 of the sinker head 3. 25

The device according to the invention is particularly suited for producing hosiery with widened heel portions whose leg and foot portions are made without interruption on one and the same machine, though it can be profitably used 30 also for making tuck pattern goods, such as twill, or for working in run stops, ladder-proof initial courses and the like.

I claim:—

1. In a flat hosiery frame a narrowing mechanism 35 for transferring loops and acting as auxiliary presser mechanism during looping, a grooved covering needle, a frame needle and a presser surface arranged above the groove of the covering needle and projecting from the plane of the latter to close the hook of the frame needle.

2. A flat hosiery frame according to claim 1, comprising a presser surface forming part of the covering needle.

3. A flat hosiery frame according to claim 1, 45 comprising a presser surface consisting of a deflection of the covering needle.

4. A flat hosiery frame according to claim 1, comprising presser means arranged on the narrowing mechanism in front of the covering needle 50 and carrying the presser surface.

5. A flat hosiery frame according to claim 1, comprising a cam having an inward bulge to permit lowering of the narrowing mechanism during 55 looping.

6. A flat hosiery frame according to claim 1, comprising supports movably disposed in the frame for holding the narrowing mechanism in inoperative position during looping.

WILLY ROTTLOFF.
